(57) **CLAIM**

The ornamental design for a scraping massage tool as shown and described.

DESCRIPTION

FIG. 1 is a first perspective view of a scraping massage tool showing my new design;

FIG. 2 is a second perspective view thereof;

FIG. 3 is a front view of FIG. 1 thereof;

FIG. 4 is a rear view of FIG. 1 thereof;

FIG. 5 is a left view of FIG. 1 thereof;

FIG. 6 is a right-side view of FIG. 1 thereof;

FIG. 7 is a top plan view of FIG. 1 thereof;

FIG. 8 is a bottom plan view of FIG. 1 thereof; and,

FIG. 9 is an enlarged view of a portion of FIG. 1 thereof. The broken lines in the drawings depict portions of the scraping massage tool that form no part of the claimed design.

The dash-dot broken lines shown in FIGS. 1 and 9 are for the purpose of showing enlarged areas, and form no part of the claimed design.
